(57) **CLAIM**

The ornamental design for a display screen with a graphical user interface element, as shown and described.

DESCRIPTION

FIG. 1 is a front view of a display screen with graphical user interface element of the new design.

FIG. 2 is a front view of a second embodiment of a display screen with graphical user interface element of the new design; and,

FIG. 3 is a front view of a third embodiment of a display screen with graphical user interface element of the new design.

The outermost broken lines in the Figures show a display screen and form no part of the claimed design. The other broken lines in the Figures show portions of the graphical user interface that form no part of the claimed design.
